UNIVERSAL SPRAY DEVICE

Oscar Zimmerman, South Bend, Ind., assignor,
by mesne assignments, to Paul Summy, War-
saw, Ind.

Application March 14, 1938, Serial No. 195,797

2 Claims. (Cl. 299—18)

This invention relates to a universal spray device for watering lawns, gardens and the like, and more particularly to a novel spray head structure.

One chief object of this invention is to provide a device which may be positioned immediately adjacent a building and/or a sidewalk and spray the area immediately adjacent the same without spraying the building or sidewalk, if the latter were of rectangular reentrant outline, or if the area between a building and sidewalk were of relatively narrow width.

Another chief object of the invention is to provide a spray device which may be adjusted for heavy, moderate or relatively light volumetric spraying.

A further object of the invention is to provide a spray device which is so constructed that the length of spray can be adjusted by regulating the supply pressure of the spraying medium.

The chief feature of the invention relates to a spraying device, the parts of which are so arranged and/or provided whereby any or all of the objects set forth may be attained therewith.

Other objects and features will be set forth more fully hereinafter.

The full nature of the invention will be understood from the accompanying drawing and the following description and claims:

10 In the drawing Fig. 1 is a top plan view of the invention.

Fig. 2 is a central sectional view taken on line 2—2 of Fig. 1 and in the direction of the arrows.

15 Fig. 3 is a diagrammatic plan view of a full circular spray effect attained with the invention.

Fig. 4 is a similar view for quarter circle spraying when the device is positioned adjacent the vertex of a reentrant angle.

20 Fig. 5 is a similar view for half circle spraying.

Fig. 6 is a similar view for three quarters circle spraying.

Fig. 7 is a similar view for spraying a relatively elongated area having a relatively narrow width.

The invention may be suitably supported. Herein a conventional type of support includes the rod 10, pointed at 11 for ground engagement. The device is furnished with water under pressure supplied by hose 12 having the threaded connecting member 13. Such a hose may be connected to a source of water pressure such as an out-door hydrant or the like (not shown).

Reference will now be had to the spray device 25 head structure illustrated in greatest detail in

Figs. 1 and 2. In these figures 14 indicates a somewhat elongated body portion having bore 15 therein. It is closed by the portion 16 having the aperture 17 therethrough. The outer end of the aperture is countersunk as at 18 and to 5 the desired depth and angle.

The lower end of the body portion is enlarged as at 19, to form seat 20. The interior of the enlarged portion has a tapered thread 21 for connection to the source of fluid supply as by 10 means of fixture 13 and the hose 12. Gasket 22 provides the usual and desired leakproof seal therebetween.

The body portion 14 and more especially the enlargement 19 herein includes a lateral extension 23, recessed as at 24 to receive the upper end of rod 10 for spray head support and device positioning. From the exterior of this enlargement there extends upwardly two elongated portions 25 each of which is adapted to extend 20 through an end link of a chain 26. These portions are upset or headed for chain anchorage.

The other end of one chain 26 is secured to an elongated blocking strip of gasket material 27 having a V-shaped groove 28 in one edge 25 and the other edge has an angular outline 29. The other end of the other chain 26 is secured to a similar strip 30 having one edge with an angular outline 31 and a straight opposite edge 32. Both strips are of resilient material and preferably are of the same thickness for a reason set forth hereinafter.

30 A cap member 33 having the knurled edge 34 and the lower chamfered face 35 is secured to a threaded stem 36 of lesser diameter than that of the aperture 17 so that when positioned in the latter an annular discharge channel is provided.

Midway of the length of the bore 15 is a nut structure 37. Diametrically arranged wings 38 extend inwardly from the bore 15, side and end walls, as shown, and support the nut structure. The wings also act to break up any swirling action of the water so that it is radially discharged from the annular channel without swirling.

40 The head structure, except for the cap, threaded stem thereof, the chains and the strip gaskets, is integral and formed from white or type metal and preferably by die casting same. If the cap and threaded stem thereof are of brass, and the same is preferred, it will be clear that the device 50 will not rust.

45 The taper of the countersunk seat 18 and the taper of the chamfered portion 35 may be the same or different. If different, the more pointed as it were, should be the seat, so that the maxi- 55

imum restriction of the discharge, if any, occurs substantially at the cap periphery rather than immediately adjacent the threaded stem 36.

- 5 The distance between the seat and cap determines the volumetric character of the spray, the lesser the distance the finer the spray and vice versa. As before stated, the length of the spray is determined by the pressure supply. Of course, these two are corelated.
- 10 The directional character of the spray may be circular in outline or otherwise as desired. When a non-circular outlined spray effect is desired, either or both of the gasket strips 27 or/and 30 may be employed by being interposed between 15 the seat 18 and cap 35 as illustrated diagrammatically in Figs. 3 to 7, inclusive. Note, that the use of two strips with adjacent portions of members 31 and 29 abutting is the equivalent of using edge 32.
- 20 While the invention has been illustrated and described in great detail in the drawing and foregoing description, the same is to be considered as illustrative and not restrictive in character.
- 25 The several modifications described herein as well as others which will readily suggest them-

selves to persons skilled in this art, all are considered to be within the broad scope of the invention, reference being had to the appended claims.

The invention claimed is:

1. A spray head structure including a body portion having a chamber therein communicating with a discharge aperture, an outwardly tapered seat defining the exterior of the aperture, the aperture being of less area than the chamber, 10 a chamfered control cap adjacent the seat, an adjustable connection between the cap and body portion for regulating the spray discharge, the body portion having a supporting portion projecting inwardly from the chamber side wall and 15 spaced from the intake end of the aperture, and swirl preventing vane means in said chamber adjacent the seat and extending between the plane of the aperture intake and inwardly projecting portion and integral therewith. 20
2. A structure as defined by claim 1, characterized by the connection being of threaded stem and nut character, the nut portion being formed in the inwardly projecting portion of the body portion. 25

OSCAR ZIMMERMAN.
